DESIGN FOR AN ADHESIVE TAPE
DISPENSER

Raymond Loewy, New York, N. Y., assignor to Industrial Tape Corporation, a corporation of
New Jersey

Application April 1, 1946, Serial No. 128,137

Term of patent 14 years

(Cl. D74—1)

To all whom it may concern:

Be it known that I, Raymond Loewy, a citizen of the United States, residing in New York, in the county of New York and State of New York, have invented a new, original, and ornamental Design for Adhesive Tape Dispensers, of which the following is a specification, reference being had to the accompanying drawing, forming part thereof.

The figure is a perspective view of an adhesive tape dispenser, showing my new design, the opposite side presenting substantially the same appearance as the side shown.

I claim:

The ornamental design for an adhesive tape dispenser, as shown and described.

RAYMOND LOEWY.
